COMPOSING MACHINES FOR PRINTING TYPES

Daniele Menta, 16 Via Cesare Balbo, Milan, Italy

Filed Jan. 3, 1966, Ser. No. 518,445

5 Claims. (Cl. 199—18)

This invention relates to improvements in, and to composing machines for printing type, or better said for lines of impression. The machines with which the invention is concerned are usually called Linotypes.

Such machines substantially comprise a keyboard by which, through a rod transmission, matrices are released. Such matrices are caused to slide by gravity along suitable grooves, and then are conveyed by a belt conveyor and a rotary star, to a collecting and lining-up station, wherefrom they are transferred by guides and lifting and lowering devices, to a station, where the casting of type line is performed. Finally, said matrices are brought, by a lifting system of the swinging arm type, and a mechanical selector, back to their cases, wherefrom they are taken again by means of the abovestated keyboard and rods, when required.

In the conventional machines, the sliding grooves, the band conveyor for the matrices and the rotary star, are fitted on the front side of machine, directly above the keyboard, and in front of rods by which the matrices are released. The sliding grooves and the belt conveyor are fitted between two plates, or flat structural elements, that are secured to the frame of machine, whereby the releasing rods, controlled by the keyboard, are covered by such elements. Said releasing rods represent, in their whole, one of the most easily perturbed mechanism of the machine, whereby they require an accurate maintenance and upkeep. However, such operations are made difficult and time-consuming by the presence of the front elements, which prevent the rods from being easily accessible.

It is accordingly a primary object of the present invention to avoid the above disadvantages.

The above drawbacks are obviated by this invention, by the provision of a machine of the above-stated type, which is essentially characterized in that the assembly consisting of the two cover plates, the grooves interposed therebetween and the belt conveyor, is pivotally connected with the machine top, and in that the belt conveyor is driven by a mechanical transmission, that is automatically engaged and disengaged as function of the position taken by the assembly, and finally in that a preferably hydraulic damper is provided to slow-down the downward motion of the above defined assembly.

The invention will be better understood from a consideration of the following description, taken with the accompanying drawing, being both description and drawing given as a not restrictive example only. In same drawing:

FIG. 1 is a front view of a composing machine, wherein the assembly by which the rods are controlled is in its operating position, i.e. before the rods.

FIG. 2 is a perspective view of a detail of same machine, with said assembly slightly lifted from its operative position, and with the front plate partly lifted from the grooves, that are normally covered by it.

FIG. 3 is a perspective view similar to that of FIG. 2, however with the control assembly wholly lifted.

Referring now to said figures, the composing machine is comprised of an assembly of devices, that are fitted on the front side thereof, above a conventional keyboard, and by which the matrice releasing rods are covered.

Said assembly consists of a bottom plate 2a, carrying the grooves 3, wherein the matrices fall, and a band conveyor 4, with the related return pulleys 5, 6 (together

2

with the required supporting and driving devices) by which the matrices are conveyed, through a settling star (not shown), to a lining-up station (also not shown). Placed before said bottom plate 2a is a further plate 7, by which the grooves 3 and a part of band 4 are covered, and that comprises a transparent sheet 8, which may consist of a slightly bent, transparent plastic sheet. The above-described assembly is pivotally fitted on a common shaft 9, whereby it can be swung upwardly to the lifted position as shown in the FIG. 3, wherein the operator can have free access to the rods 2 which, as already stated, cause the matrices, corresponding to keys depressed by the operator, to fall into the grooves.

The assembly is retained in its lifted position by a latch 10, which will be described in more detail later, and is kept in its down position—i.e. in its operating position by two hooks 11, that are designed to cooperate with a bar 12a, which forms part of the machine frame, and that can be disengaged therefrom by acting on a handle 12.

Indirectly connected with 14 is a damper 13, whose opposite end is hinged to any suitable point of machine frame 12, as e.g. 15, and by which the bottom plate 2a is acted upon, in order to cause a smooth and slow down motion of the above-stated assembly.

In more detail, the upper plate 7, by which the drop grooves are covered, can be swung round the common shaft 9, independently from the other plate 2a, and can be retained in its lifted position (see FIG. 2) by the same latch 19, that serves also to keep the whole assembly in its lifted position, as shown in the FIG. 3.

Formed on the front side of bottom plate 2a, is a series of grooves 3 extending in a substantially vertical direction, and having lengths which decrease from the left to the right, such grooves being delimited on one side by plate 2a, on two further sides by parallel laths 16, that are fastened in any known, suitable manner, to same plate, and on the fourth side by the top plate 7.

The matrices that fall down the grooves 3 come into contact with the length of belt conveyor 4 that runs over a slanting wall 17, which is located below the lower ends of grooves 3, and is secured to the plate 2a.

The band conveyor runs around the two return pulleys, that are loose fitted on supports (not shown), with which the plate 1 is provided. The shaft 18 of lower pulley 5 extends through the plate 2a and carries, keyed on its outer end, a gear 22 and a further pulley 19, that is driven, through a belt transmission 20, by a driving pulley 21, which is also loose fitted on said bottom plate. A helical toothed crown gear 23, that is formed on the bottom of cup-shaped driving pulley 21, is designed to cooperate, when the plate 2a is in its down position, with an also helical toothed face gear 24 which drive is derived, in any known suitable manner, from any driven component of the composing machine.

In mesh with said gear 22 is the first gear of a gear train 25, through which the rotary star is driven. The matrices delivered by the band conveyor 4 are received by such star, and then transferred in the proper sequence, to lining-up station. Said settling star is already well known, and in the considered example is supported on the outer face of bottom plate 2.

The bottom plate 2a, along with the different components fitted thereto, is swingingly fitted on the stationary shaft 9, which is in turn supported by the outer ends of a pair of arms 30, that are secured in any known, suitable manner, to the machine frame.

Secured by screws to lower side of bottom plate 2a are two arms carrying the bushes 32 at their outer ends, said bushes being engaged with the shaft 9.

The one of said two arms (i.e. that indicated by the numeral 31a) is crosswise recessed as in 31a for the pur-

pose which will be hereinafter stated, whereby a wedge-shaped cross-section, having its vertex directed to the right side of the operator, is given to recessed portion of said arm.

Also hinged to the shaft 9 is the upper plate 7, by which the downfall grooves 3 and the inclined plate whereon the band conveyor 4 is running, are covered. Said plate is supported by the shaft 9 by means of a pair of arms 34, having a circular or triangular cross-section, and its top is connected, in any known, suitable manner, with the transparent sheet 8.

Moreover, a fork 36 is cantilever supported by the bottom plate 2a. One end of the piston rod 37 of hydraulic damper 13 is pivotally connected (as in 14) with a pin, extending between the arms of said fork 36, being the opposite end of said damper hinged to a stirrup (as in 15), that is cantilever supported by the frame of the machine.

Secured to a support (the right one in the drawings) of the shaft 9 is a latch 10, that consists of a bolt 38, that is slidingly fitted against the action of return springs (not shown), and having one end suitably beveled, while a grip 39 is carried by its opposite end. Same latch is positioned in such a manner that it can be automatically shifted, against the action of its return spring, by the right arm 34, by which the cover plate 7 is supported, thereby coming into engagement with the transverse recess 33 of the right arm 31a, by which the bottom plate 2a, is supported, and that provides for the further shifting, when said plate is lifted. In the wholly lifted position of same plate, a tripping of same bolt under the two above mentioned arms occur, whereby the whole assembly is retained in its lifted position. When the assembly is to be brought down, the bolt is brought back by the operator, acting on its grip, thereby disengaging it from the arms of both plates.

To have the bottom plate 2a rigidly connected with the machine frame when the assembly is in its operating position, two fork-shaped supports 41 are secured to bottom side of the same plate. Each one of said supports is revolvably fitted in a square-shaped hooking-up device, that is designed to get engaged with the bar 12a, which forms a part of the stationary frame of machine. A control revolving shaft 50, laid on the supports 44, and carrying a grip 12b on one of their bent ends, is provided for turning, and thus disengaging said hooking-up devices. Said shaft is formed with cam tracks, by which said devices are acted upon whereby, when it is operated, the hooking-up devices are turned, and thus disengaged.

In more detail, the hooking-up devices 11 are L-shaped (see FIG. 3), having a hook extension formed at the end of one of their arms. A compression spring 43, that is interposed between the stirrup support 44 and said arm of L-shaped element, tends to maintain the hook end into engagement with the bar 12a.

Due to the above described arrangement, the operator is enabled to disengage the bottom plate 7 from the bar 12a, by acting on the grip 12b, whereafter same plate can be swung round the rotation shaft 9. At the end of said upward motion, the latch bolt is firstly shifted over the arm 34, by which the cover plate 7 is supported, becoming engaged with the recess 33 of element 31a, beneath it, whereby the whole assembly is retained in its lifted position.

Then the assembly is to be brought down to its operating position, it will be sufficient, for the operator, to pull the latch grip 39 to the right, whereby the assembly is brought down, to its operating position in a wholly automatic manner, the downward motion being slowed down and controlled by the damper. In said operating position, the hooking-up devices are automatically engaged with the bar 12a, and the two helical gears 23, 24 are brought into mesh with each other. As shown in the FIG. 2, the upper wall or plate 7 can be moved inde-

pendently from the bottom plate 2a, and can be retained in such a position by the latch.

While the invention has been described in detail with respect to one, now preferred embodiment thereof, it will be understood by those skilled in the art, after understanding the invention, that various changes and modifications may be made without departing from the true spirit and scope thereof, and is intended, therefore, to cover all such changes and modifications in the appended claims.

I claim:

1. In a composing machine having a keyboard and a plurality of rods selectively actuated by said keyboard for releasing selected matrices, swingable means having an operating position situated in front of said rods and including a pair of plates between which a grooved structure is situated for guiding the released matrices for movement between said plates, said swingable means also including between said plates a rotary belt means, transmission means for driving said rotary belt means and including motion-transmitting components one of which is carried by said swingable means and the other of which is carried by said machine at a location which is situated beyond said rods so that said other component of said transmission means does not prevent access to said rods, said components of said transmission means being in operative driving engagement with each other when said swingable means is in said operating position thereof, and a stationary shaft operatively connected with said swingable means to support the latter for swinging movement away from said operating position to a location giving free access to said rods and back to said operating position situated in front of said rods, said components of said transmission means automatically resuming their operative driving engagement with each other upon return of said swingable means to said operating position thereof.

2. The combination of claim 1 and wherein both of said plates are independently turnable on said stationary shaft, said shaft being horizontal and said swingable means extending downwardly from said shaft when in its operating position and being turned upwardly away from said operating position to said location giving access to said rods, and releasable latch means coacting with said swingable means for releasably retaining the latter at said location, whereby upon release of said latch means said swingable means will by gravity swing automatically back down to its operating position.

3. The combination of claim 2 and wherein a damping means coacts with said swingable means for retarding the downward movement thereof back to said operating position.

4. The combination of claim 3 and wherein said plates include a lower plate and an upper plate, and said lower plate carrying said grooved structure and said rotary belt means as well as that component of said transmission means which is connected with said swingable means.

5. The combination of claim 4 and wherein said latch means is selectively operable with said upper plate, independently of said lower plate, to give access to the structure carried by said lower plate when said upper plate only is turned about said shaft upwardly away from said operating position to said location.
